GOVERNOR CONSTRUCTION

John L. Moody, Oakland, Calif., assignor to
 Friden Calculating Machine Co., Inc., a corporation of California

Application April 8, 1940, Serial No. 328,473

7 Claims. (Cl. 200—80)

This invention relates to governors, and is concerned more particularly with the provision of improved governing means for electric motors of the constant speed type, such as those employed, for example, in driving calculating machines.

In electric motors adapted for constant speed operation from a direct current source of supply, considerable trouble and annoyance has been caused at the make-and-break contacts of the governor because of the building up of material on one contact from the other contact so that the contacts become rough. These difficulties have caused frequent replacement of the points of the governor contacts and in some instances entire replacement of the governor in an unduly short time.

The instant invention is designed to obviate the foregoing difficulties and to provide a governor which can be employed equally well with both alternating current and direct current electric motors, and which particularly is adapted for use with direct current motors by providing self-cleaning points in the make-and-break contacts, so that pitting and roughening of such contacts cannot occur.

It is a general object of the invention, therefore, to provide an improved governor construction for electric motors.

Another object of the invention is to provide a governor construction of the above type which is particularly adapted for use with direct current motors.

Another object of the invention is to provide improved self cleaning contact points for the governor of a direct current motor.

Other objects and advantages will be apparent from the following description of certain preferred embodiments of the invention as illustrated in the accompanying drawings, in which:

Figure 1 is an end elevational view of the governor construction embodying my invention as mounted on an electric motor;

Figure 2 is a sectional elevational view of the governor shown in Figure 1, the view being taken in a plane indicated by the line 2—2 in Figure 1;

Figure 3 is a sectional elevation of the governor construction, the view being indicated by the line 3—3 in Figure 2;

Figure 4 is a sectional elevation of the governor construction, the view being taken as indicated by the line 4—4 in Figure 2;

Figure 5 is an end elevational view of a second governor construction embodying my invention;

Figure 6 is a sectional view through the governor shown in Figure 5, the plane of the view be-

ing indicated by the line 6—6 in Figure 5; and Figure 7 is a sectional elevational view taken in a plane indicated by the line 7—7 in Figure 6. Referring to Figures 1 to 4, the governor of my invention is shown as applied to an electric motor 10 having a drive shaft 11 and having opposite casing extensions 12 to provide a mounting for the governor. Across the extensions 12 of the motor casing, an insulating plate 13 may be secured as by screws 14.

The motor shaft 11 has a collar 16 secured thereon as by a set screw 17 (Figure 3). The collar 16 is reduced in diameter at one end to receive a U-shaped bracket 18 which is first inserted on the reduced portion of the collar 16 and the end of this portion is then peened or swedged over to hold the bracket 18 in place. The bracket 18 is provided on one side with opposite ears 19 to receive a pivot pin 21 which also passes through inturned ears 22 of a governing lever 23 of L-shape which has its length disposed substantially axially of the shaft 11. The inner end of the governing lever 23 (Figure 3) is forked to embrace the round shoulder 24 of a square collar 26 secured on a governing shaft 27 as by means of a set screw 28 (Figure 4). The turned end 24 of collar 26 is slidably and rotatably disposed within a recess 29 of motor shaft 11. The square portion of collar 26 slidably engages within a square opening in the bracket 18 whereby the collar 26 and the shaft 27 are rotated with the motor shaft 11.

The governing shaft 27, therefore, is mounted for rotation with the motor shaft 11 and for axial movement. Shaft 27 is preferably formed of suitable insulating material, such as "Bakelite."

Shaft 27 extends outwardly from collar 26 into an opening 31 of the plate 13 where it carries a collar 32 of conducting material secured thereon as by a set screw 33. At one end collar 32 carries an annular contact point 34 adapted for engagement with an opposed contact point 36 which is mounted on a collar 37 supported by conducting bracket 38 on plate 13 to which the bracket 38 is secured as by screws 39. One conducting wire in the motor circuit may be connected to one of the screws 39.

The outer end of the conducting collar 32 is reduced and has secured thereto a contact point 41 adapted for engagement with a second stationary contact 42 supported by an arm 43. Arm 43 is pivoted as by pin 44 on a bracket 46 suitably secured on the plate 13. Intermediate its ends, the arm 43 is provided with offset portion 47 forming a seat for one end of spring 48

having its other end seated on washer 49 carried by adjusting screw 51. Screw 51 is threaded into the plate 13 and is secured in adjustment with respect thereto by the nut 52. To complete the motor circuit, a second conducting wire 5 may be secured as by soldering to the lever 43 so that lever 43, contact points 41, 42, collar 32, contact points 34, 36, collar 37 and bracket 38 all form a part of the motor circuit.

In operation, the screw 51 is adjusted so that the desired compression is placed on spring 48 to resist endwise movement of the governing shaft assembly 27 under the thrust of the governing lever 23. When the revolutions of the motor exceed the adjustment of the spring 48, 10 governing lever 23 becomes effective under centrifugal force to act against collar 26 and move shaft 27 endwise to compress spring 48 and separate contact points 34 and 36 and thereby break the motor circuit. The circuit remains 15 broken until the revolutions of the motor have decreased to again permit the spring 48 to become effective and urge the contact points 34 and 36 back into engagement. It will be noted that both sets of contact points 34, 36 and 41, 42 20 are always subject to relative rotation to provide a self-cleaning action and prevent any build-up from one contact to the other so that an even and bright conducting face is always available for carrying the current to the motor. Also, screw 51 is located in an accessible position 25 to enable adjustment of spring 48 while the governor and motor are operating.

Referring to Figures 5 to 7, a modified form of construction is provided wherein the governing lever is mounted in statically counter-balanced relation with respect to the axis of rotation. Similar parts are numbered similarly.

The construction includes a motor 10 having a motor drive shaft 11a with a reduced end on 40 which a collar 16a is secured as by a set screw 17. The collar 16a is provided with a diametral slot 61 and is also recessed at 62 to receive sleeve 63 secured on governing shaft 27 by set screw 64. Sleeve 63 is also provided with a diametral slot 45 to receive a governing arm 65 disposed in the diametral slot 61 in sleeve 63a and pivoted therein as by a pin 66. The governing member 65 is symmetrical with respect to the axis of rotation of the motor shaft 11a so as to be statically balanced. However, the pivot point 68 is offset so that the governor arm will swing under the effect of centrifugal force from its rest position as shown in Figure 6 in the direction indicated by the arrow to effect endwise movement of collar 55 63 and shaft 27.

Shaft 27 carries conducting collar 32 having respective contacts 34 and 41 secured thereon for cooperation with respective contacts 36 and 42. Contact 36 is carried by collar 37 mounted in bracket strip 38a secured on plate 13 as by bolts 39a to which one of the motor leadwires is secured. Contact 41 is in constant engagement with opposed contact 42 which is carried by adjusting lever 43a pivoted at 44a on bracket 46a and having its opposite end engaged by compression spring 48a seated against the end of adjusting screw 51a threaded in plate 13.

The operation of the above governor is similar in all respects to that as described in connection with Figures 1 to 5 except that the action of the governing member 65 provides a very sensitive construction because of its counter-balanced relation with respect to the axis of rotation.

I claim:

1. In an electric motor governor, a governing shaft mounted for axial movement in alignment with the motor shaft, said shafts being connected for simultaneous rotation, a governing element mounted for rotation with said motor shaft and connected to said governing shaft to effect said endwise movement thereof, a rotating contact carried by said governing shaft, a non-rotatable contact mounted for cooperation with said rotating contact, endwise movement of said governing shaft effecting opening and closing of said contacts, and spring urged means for resisting endwise movement of said shaft, said means including adjusting means for varying the tension of said spring urged means.

2. In an electric motor governor, a governing shaft mounted for axial movement in alignment with the motor shaft, said shafts being connected for simultaneous rotation, a governing element mounted for rotation with said motor shaft and connected to said governing shaft to effect said endwise movement thereof, a rotating contact carried by said governing shaft, a non-rotatable contact mounted for cooperation with said rotating contact, endwise movement of said governing shaft effecting opening and closing of said contacts, a second rotating contact carried by said governing shaft, and a second non-rotatable contact in cooperative engagement with said second rotating contact, and spring urged means for maintaining said last named pair of contacts in engagement.

3. In an electric motor governor, a motor shaft, a governing shaft mounted for axial movement, said shafts being connected for simultaneous rotation, a governing element mounted for rotation with the motor shaft and connected to said governing shaft to effect said endwise movement thereof, a pair of electrically connected rotating contacts carried by said governing shaft, and a pair of contacts mounted for cooperation respectively with said rotating contacts, endwise movement of said governing shaft effecting opening and closing of at least one pair of said contacts.

4. In an electric motor governor, a governing shaft formed of insulating material and mounted for axial movement in alignment with the motor shaft, said shafts being connected for simultaneous movement, a governing element mounted for rotation with said motor shaft and connected to said governing shaft to effect axial movement upon increase of speed of said motor, a pair of rotating contacts on said governing shaft, and a pair of non-rotatable contacts for engagement respectively with said rotating contacts, endwise movement of said governing shaft effecting opening and closing of one pair of said contacts.

5. In an electric motor governor, a governing shaft formed of insulating material and mounted for axial movement in alignment with the motor shaft, said shafts being connected for simultaneous movement, a governing element mounted for rotation with said motor shaft and connected to said governing shaft to effect axial movement thereof away from said motor shaft upon increase of speed of said motor, a pair of rotating contacts on said governing shaft, a pair of stationary contacts mounted for engagement respectively with said rotating contacts, endwise movement of said governing shaft effecting opening and closing of one pair of said contacts.

6. In a governor for an electric motor having

a drive shaft, a collar mounted on said drive shaft having a diametral slot, a governing member extending through said slot in substantially counterbalanced relation with respect to the axis of said shaft, said element having an off-center pivotal connection with said collar, a governing shaft mounted for endwise movement in axial alignment with said motor shaft, said governing shaft having an end disposed for engagement by said governing member, and contact means 10 adapted for opening and closing movement by said governing shaft.

7. In a governor for an electric motor having a drive shaft, a collar mounted on said drive shaft having a diametral slot, a governing mem- 15

ber extending through said slot in substantially counterbalanced relation with respect to the axis of said shaft, said element having an off-center pivotal connection with said collar, a governing shaft mounted for endwise movement in axial alignment with said motor shaft, said governing shaft having an end disposed for engagement by said governing member, and contact means adapted for opening and closing by movement of said governing shaft, one of said contacts being connected to said governing shaft for rotation therewith and the other of said contacts being stationary and adapted for engagement with said rotating contact.

JOHN L. MOODY.
